RECEPTACLE

Filed April 29, 1925

UNITED STATES PATENT OFFICE.

HENRY TOPPIN AND ARTHUR G. STEVENSON, OF ROCHESTER, NEW YORK, AS
SIGNORS TO THE F. A. SMITH MANUFACTURING CO. INC., OF ROCHESTER, NEW
YORK, A CORPORATION OF NEW YORK.

RECEPTACLE.

Application filed April 29, 1925. Serial No. 26,796.

This invention relates to receptacles and, more particularly, to the variety adapted for holding smokers' articles, such as cigarettes and the like, one object of the invention being to provide an improved receptacle for dispensing cigarettes of a more convenient and practical form of construction and one especially suitable for attachment to the dash or other part of an automobile. Another object is the provision of such a receptacle capable of holding a relatively large number of cigarettes of the same kind, or of different kinds separately, and combined in a compact and complete smoker's kit, comprising also, for instance, receptacles for holding matches and receiving ashes accessibly arranged to facilitate use thereof by an automobile driver, for example, with one hand and with the least distraction of the attention from the operation of the vehicle.

To these and other ends the invention resides in certain improvements and combinations of parts, all as will be hereinafter more fully described, the novel features being pointed out in the claims at the end of the specification.

In the drawings:—

Figure 1 is a front elevation of receptacle means embodying the present invention;

Figure 2 is a side elevation of the same as viewed from the left in Figure 1;

Figure 3 is a rear elevation of the same;

Figure 4 is a sectional view on the line 4^a—4^a in Figure 1;

Figure 5 is an enlarged sectional view on the line 5^a—5^a in Figure 3, illustrating a detail of construction;

Figure 6 is a sectional plan view on the line 6^a—6^a in Figure 3, illustrating the ejection of a cigarette, and

Figure 7 is a perspective view of an ejecting slide detached.

Similar reference numerals throughout the several views indicate the same parts.

The embodiment of the invention herein disclosed, by way of illustration, is intended more especially for holding and dispensing cigarettes, but the invention is of course applicable for use also with cigars and like articles. The receptacle is preferably constructed of sheet metal in the substantially rectangular and upright shape shown, comprising a front wall 10, rear wall 11, end walls 12 and 13, respectively, and a bottom 14. The

front and end walls are preferably formed from a single blank and the rear wall and bottom from another, the end walls carrying lugs 12^a passed through eyes in the rear wall and clinched as shown in Figure 5. The receptacle has an open top serving as a filling opening, closed by a cover 15 hinged at the rear as at 16. A partition 17 divides the receptacle into separate compartments 18 and 19, each of which is adapted to hold an upwardly extending row or column of cigarettes 20 laid horizontally one upon another as shown, with the lowermost one in each compartment resting on the bottom 14. The compartments may be quickly filled by raising the cover 15 and dropping the cigarettes into them and the provision of a plurality of compartments arranged as shown affords a relatively large capacity for the receptacle. If desired, different kinds of cigarettes may be placed and held separately in the respective compartments.

The receptacle is formed with a dispensing opening preferably arranged adjacent the bottom of the end wall 13. In the present instance the wall is formed at this point with an opening covered by a plate 21 riveted or otherwise secured thereto and having its central portion spun outwardly as at 22 and formed with the dispensing opening proper, 23. This opening has its center located opposite the partition 17, which is cut away adjacent the opening as at 24, Figure 3, and the inclined plate portions 22 serve to guide a cigarette projected longitudinally from the bottom of either compartment into the dispensing opening 23 which is thus common to both compartments, as shown in Figure 6. But one cigarette of course can enter the opening at a time.

The devices for ejecting the cigarettes comprise guide means preferably disposed below the bottom 14 of the receptacle and in the present instance in the form of rectangular bars 25 fixed at their ends in the end walls 12 and 13. Sliding on each of these bars is a slide or plate 26 having upturned ends 27 and 28 containing rectangular openings through which the guide bars 25 are inserted. The end 28 of each slide has a finger 29 extending upwardly through a slot 30 in the bottom of each compartment adjacent the end 12 of the receptacle, the upper end of the finger being enlarged as shown for

substantial engagement with the end of the lowermost cigarette for pushing the same longitudinally into the discharge opening. End 12 of the receptacle is bowed outwardly at its bottom as at 31 to provide a recess in the wall in which ejecting fingers 29 normally lie, the ejecting slides being urged towards this end of the receptacle by springs 32 coiled about bars 25 between the slides and the opposite end wall. Slides 26 carry manually operable means in the form of downwardly extending posts or handles 33 for operation by a finger to eject the cigarette. It is to be noted that the operating means 33 of the forward slide 26 is located at the end of the slide adjacent the end wall of the receptacle while the corresponding means or handle of the rear slide is located at the opposite end of the latter and thus spaced inwardly of the receptacle from the handle of the forward slide.

With this arrangement, as a finger is swept across the bottom of the receptacle from right to left, the right hand or forward handle 33 is engaged and moved toward the left so that the lowermost cigarette of the corresponding forward compartment is moved to eject its end for a substantial distance through the dispensing opening 23, as shown in Figure 6. Should the other or rear handle 33 be inadvertently engaged, it cannot however eject a cigarette because of the prior operation of the other post and the closing of the opening by the cigarette from the forward compartment. In the normal operation of the receptacle, therefore, cigarettes are ejected from the forward compartment until the latter becomes empty after which the finger is moved across the bottom of the receptacle until it engages and operates the left or rear handle also, which results in the ejection of a cigarette from the rear compartment. If desired however different kinds of cigarettes may be placed in the compartments and the normal method of operation described above varied by selecting for operation individually the handle 33 corresponding to the desired variety.

Means are provided for attaching the receptacle in fixed position on a support such, for example, as the dash or window panel of a vehicle, the attaching means being preferably of such a variety as to adapt the same for application to either a horizontally or vertically extending support. To this end the rear wall of the receptacle is formed with rearwardly struck strips 34 and 35 aligned in horizontal and vertical pairs, respectively, as shown in Figure 3. An elongated plate 36 is adapted to be inserted endwise through either pair of strips 34 or 35, the plate being of such length as to project at its ends beyond the receptacle and being provided with openings 37 for screws for attaching the same to a support. Plate 36 is shown in the present

instance as applied to the receptacle through strips 34 in horizontal position but it may obviously be withdrawn from such position and engaged under the strips 35 in vertical position as useful for example in securing the receptacle to a vertical window panel.

The receptacle constructed as described is preferably combined in a complete and compact smoker's kit comprising also match holding and ash receiving receptacles. For this purpose the front wall 10 is preferably arranged to afford a plane surface and has secured thereto at its opposite ends, the ends 38 of a plate 39 having the generally channel shape best shown in Figure 6. The lower edges of the plate are turned inwardly to provide horizontal supporting flanges 40 and the forward sides of the plate has an inturned central vertical rib 41 formed therein to separate the space enclosed between the plate and the front of the receptacle into two compartments. One of these is adapted to receive an ordinary safety match box which may be disposed therein with the end of the box removed in the usual manner to expose the matches for withdrawal and the plate 39 may be cut away at the end of this compartment as at 39^a, Figure 4, to expose the portion of the box provided for striking the match. The other compartment in plate 39 is preferably provided with an open topped metal box 42 serving as an ash receiver, detachably carried in its compartment for removal and emptying as required. The front wall 10 preferably has spring fingers 10^a struck therefrom as shown to yieldably retain the match box and ash receiver in place.

The invention thus provides a compact receptacle for a considerable number of cigarettes and the same or different kinds, being readily filled by raising the cover 15. A single sweep of the finger from right to left across the bottom of the receptacle serves to partially eject a cigarette through the opening at the left of the receptacle, the handles 33 being arranged to effect operation thereof successively to eject the cigarettes one at a time, first from the forward compartment and then from the rear until both are empty. In case different varieties of cigarettes are placed in the respective compartments, the handles may be operated selectively and independently for ejecting the desired variety. The receptacle so constructed is compactly combined in a complete smoker's kit so arranged that the driver of a vehicle, for example, need remove but one hand from the steering wheel to obtain a cigarette and a match to light the same and this may be done in a simple and rapid manner so as to distract the attention to the least extent from the operation of the vehicle. The kit may be readily positioned as found convenient, by means of the simple and effective attaching device adapted to be secured to either horizontally

or vertically extending panels and is preferably given an ornamental finish enhanced by symmetry of proportions and arrangement of parts to afford an attachment of pleasing 5 appearance.

We claim as our invention:

1. A dispensing receptacle for elongated articles having therein a fixed partition dividing the same into separate compartments each adapted to contain an upwardly extending row of articles, a common dispensing opening in constant communication with said compartments for supplying an article longitudinally from either compartment, and a plurality of ejecting means, one for each compartment, arranged to normally effect operation thereof successively and the ejection of the articles one at a time.
2. A cigarette receptacle having therein a fixed partition dividing the same into separate compartments each adapted to contain an upwardly extending row of cigarettes, a common dispensing opening for supplying a cigarette longitudinally from either compartment, and a plurality of ejecting means, one for each compartment, having manually operable means arranged one in advance of the other for normally effecting operation thereof individually to eject the cigarettes one at a time through said dispensing opening.
3. A cigarette receptacle comprising side walls and a bottom and a partition therein dividing the same into separate compartments each adapted to contain an upwardly extending row of cigarettes, said receptacle having a filling opening adjacent its top and a dispensing opening adjacent the bottom of one of said side walls, means for attaching 40 the receptacle to a support, a plurality of

ejecting means, one for each of said compartments, and manually operable means for said ejecting means, arranged one in advance of the other to effect operation thereof individually to eject the cigarettes one at 45 a time through said dispensing opening.

4. A cigarette dispensing receptacle comprising a plurality of separate compartments each arranged to contain a supply of cigarettes, the longitudinal axes of the cigarettes 50 in one compartment being substantially parallel to the axes of those in another compartment, said receptacle having a dispensing opening common to said compartments but out of direct alinement with the longitudinal axes of cigarettes about to be dispensed from said compartments, means for displacing a cigarette longitudinally from a selected one of said compartments, and guiding means arranged to deflect a cigarette during its longitudinal displacement to cause it to pass through said common dispensing opening irrespective of the compartment from which said cigarette was ejected.

5. A cigarette dispensing receptacle having a partition therein to divide the receptacle into two compartments each arranged to contain a supply of horizontally extending cigarettes, the longitudinal axes of the cigarettes in each compartment being substantially 70 parallel to said partition, means for displacing a cigarette longitudinally from either one of said compartments selectively, and convergent guiding means for deflecting a cigarette during its longitudinal displacement to cause it to pass through a common dispensing opening substantially in alinement with said partition.

HENRY TOPPIN.

ARTHUR G. STEVENSON.
